VANITY COMPACT

Filed Jan. 14, 1929

INVENTOR,
JACOB CARROLL ANDERSON
By Frederick C. Bromley
Attorney.

UNITED STATES PATENT OFFICE

JACOB CARROLL ANDERSON, OF OSHAWA, ONTARIO, CANADA

VANITY COMPACT

Application filed January 14, 1929. Serial No. 332,334.

The invention relates to improvements in vanity compacts as described in the present specification and shown in the accompanying drawings which form part of the same.

5 The present invention has for its object the production of a vanity compact in which is incorporated an electric light that is automatically switched on and off by the opening and closing of the lid. The lamp is designed to shed its light not only upon the mirror but also upon the articles of toilet. As will be readily realized this illumination is exceedingly desirable in that it enables the user to more clearly observe herself when attending to her toilet and is particularly convenient for dimly lighted places such as theatres, et cetera.

15 A distinctive characteristic of the invention is that the battery is stored beneath the trays containing the articles of toilet and is removable through a hinged end of the casing, the bulb and switch being mounted upon the swingable end in order to provide a unitary structure that does not interfere with 25 insertion and removal of the battery.

Referring to the drawings, Figure 1 is a perspective view of a compact constructed and arranged according to the present invention. In this view the lid is shown open.

30 Figure 2 is a plan view of Figure 1, a portion of the trays being broken away to show the position of the battery therebeneath.

Figure 3 is a transverse section taken on the line 3—3 of Figure 2 depicting the electric switch closed.

Figure 4 is a similar section but illustrating the lid closed and the switch open.

Figure 5 is a perspective view of the compact illustrating the lid open and the hinged end of the casing swung out to permit of insertion or removal of battery, a portion of the near side of the casing being broken away to show the battery to better advantage.

Like numerals of reference indicate corresponding parts in each of the figures throughout the drawings.

In the drawings, the reference numeral 10 denotes in a general way the body of the casing which is preferably but not essentially of an irregular rectangular shape in plan and

has the usual lid 11 hingedly connected as customary along one side. The lid may bear the mirror 12 while the interior of the body is provided with shallow trays as at 13 or other divisional elements for holding the articles of toilet. These it is proposed shall extend lengthwise and terminate short of one end of the body so as to leave a space to accommodate the electric light bulb and switch mechanism. The end of the body 14 at which this space occurs is hinged as at 14' to the bottom 15 and retained in a normally closed position by catches, not shown since they may be of conventional type.

The body of the casing is of a greater depth 65 than the trays 13 so as to form a compartment therebeneath to accommodate the battery 16. When the hinged end 14 is open this compartment is accessible for the purpose of inserting and removing the battery. 70

The bulb 17 is fitted in a socket 18 attached to the hinged end 14 and the base of the bulb protrudes through the socket so as to make, contact with the prong 19 of the battery. A bracket 20 is rigidly attached to the said end 75 14 in the vicinity of the hinged side of the lid 11 and has a vertical plunger 21 slidably mounted in it. The upper end of this plunger has a head 22 for contact with the lid aforesaid and is normally held raised by a compression spring 23. The lower end of the plunger projects through the bracket and terminates in a contact 24 that is held in engagement with the contact 25 rigidly extending from the socket 18. 80

Rigidly projecting from the bracket is a finger 26 that has a curled end 27 bearing against the second prong 29 of the battery. 85

It will be manifest that by the aforesaid construction the circuit is closed and the lamp lit as long as the lid remains open, but upon its being closed the plunger is depressed, thus shifting its contact 24 away from the contact 25 and opening the circuit. 90

Furthermore, it will be evident that upon opening the end 14 of the body the electric lamp and its mechanism is thrown clear of the battery thus rendering the lamp and switch accessible as well as providing for the battery's removal. 100

What I claim is:—

In a vanity compact, a casing body of an elongated shape in plan, one end of said casing being hingedly connected, an arrangement of toilet trays in said body terminating short of said hinged end to provide space to accommodate a lamp proper and switch, the depth of the casing body being greater than that of the trays thus leaving a compartment therebeneath, a battery fitted in said compartment, and a lamp proper and switch unit borne by the inner side of the hinged end of the casing body and adapted to electrically contact with the battery prongs when the hinged end is closed.

Signed at Oshawa, Ontario, Canada, the 3rd day of January, 1929.
JACOB CARROLL ANDERSON.
